UNITED STATES PATENT OFFICE.

FREDERICK J. EDGARS, OF BROOKLYN, NEW YORK.

DESIGN FOR A WOODEN BOX.

SPECIFICATION forming part of Design No. 23,896, dated December 25, 1894.

Application filed October 31, 1894. Serial No. 527,585. Term of patent 7 years.

To all whom it may concern:

Be it known that I, FREDERICK J. EDGARS, a citizen of the United States, residing at Brooklyn, in the county of Kings and State of New York, have invented and produced a new and original Design for a Wooden Box, of which the following is a specification.

In the drawing I have represented my design by a vertical section.

- 10 The general configuration of the box is round, and the leading features of my design consist in the plain central portion and the ribs and coves at the respective ends and the intermediate plain bands.
- 15 The design of the cover A comprises the rounded end *a*, the tapering top *b* and beaded edge *c*, the cove *d*, the rib *e*, the intermediate

plain bands 1, 2, 3 and the plain parallel sided portion *f*.

The design of the body portion B comprises 20 the plain nearly parallel sided portion *f'*, a continuation of the portion *f* of the cover, the rib *h*, cove *i* and curbed base *k*, and the intermediate plain bands 4, 5, and 6.

What I claim is—

The design for a wooden box substantially 25 as shown and described.

Signed by me this 29th day of October, A.D. 1894.

FREDERICK J. EDGARS.
